Roy L. Jackson Inventor

By Richard Oliver,

Attorney

UNITED STATES PATENT OFFICE.

ROY L. JACKSON, OF MARION, ALABAMA.

THUMB-GUARD.

1,161,478.

Specification of Letters Patent. Patented Nov. 23, 1915.

Application filed October 7, 1914. Serial No. 865,572.

To all whom it may concern:

Be it known that I, ROY L. JACKSON, a citizen of the United States, residing at Marion, in the county of Perry and State of Alabama, have invented certain new and useful Improvements in Thumb-Guards, of which the following is a specification.

This invention relates to devices for preventing infants or small children from sucking their thumbs, and has for one of its objects to improve the construction and increase the efficiency of devices of this character.

Another object of the invention is to provide a device of this character which is simple in construction and sanitary and positive in its operation.

Other objects will appear and be better understood in reading the annexed specification in connection with the accompanying drawings, in which:

Figure 1 is a perspective view showing the device applied; Fig. 2 is a similar view of the device removed.

Referring to the drawings by numerals, 5 designates a circular ring of wire, or other suitable material, to which is fastened, in any suitable manner, the ends of a pair of spaced wires or guards 6. The wires 6 at 30 their opposite ends, are formed with eyes 7, through which is passed a tape or other suitable fastening element 8, the purpose of which will subsequently appear.

A second pair of wires or guards 9, are 35 fastened to the ring 5 in spaced relation thereto and extend in the same general direction as the wires 6, but are of shorter length than the wires 6, and are fastened thereto by means of the ring 10, which ring 40 is soldered or otherwise secured to the ends of the wires 9, and to the wires 6, intermediate the ends thereof.

In order to strengthen the ends of the wires 6 and hold the same in their spaced relation, an arcuately shaped wire or brace 45 11 is provided to connect the wires 6 intermediate the eyes 7 and the ring 10.

In applying the device to the hand of a child, the thumb is first entered in the opening of the ring 10 and the device so positioned that the wires 6 extend over the back of the hand with the tape or other fastening element in a position to be passed around the wrist. In fastening the device, the tape is 55 first passed around the wrist of the wearer, one end passed through the palm of the

hand and fastened to the ring 10, and then extended over the back of the hand and tied to the opposite end of the tape.

A child, having a device as above set forth 60 applied to its hand, will, after a few attempts to suck its thumb, find that such action is impossible, and will be gradually weaned from such practice.

I claim:

1. A thumb sucking preventer comprising a plurality of longitudinally arranged wires adapted to inclose the thumb, certain of said wires terminating at the inner portion of the thumb, other of said wires being relatively longer than said first-mentioned wires and adapted to extend over the back of the thumb, means to secure the wires in spaced relation; and means to secure the device to the hand.

2. A thumb sucking preventer comprising a plurality of longitudinally arranged wires adapted to inclose the thumb, certain of said wires terminating at the inner portion of the thumb, other of said wires being relatively longer than the said first-mentioned wires and adapted to extend over the back of the thumb, a plurality of rings for connecting said wires in spaced relation, and means to secure the device to the hand.

3. A thumb sucking preventer comprising a plurality of longitudinally arranged wires adapted to inclose the thumb, certain of said wires terminating at the inner portion of the thumb, other of said wires being relatively longer than the said first-mentioned wires and adapted to extend over the back of the thumb, a plurality of rings for connecting said wires in spaced relation, a brace to strengthen said wires, and means to secure the device to the hand.

4. A thumb sucking preventer comprising a plurality of longitudinally arranged wires adapted to inclose the thumb, certain of said wires terminating at the inner portion of the thumb, other of said wires being relatively longer than the said first-mentioned wires and adapted to extend over the back of the thumb, a ring for connecting said wires in spaced relation, a second ring to which the inner ends of the shorter wires are connected, a brace to strengthen said wires, and means to secure the device to the hand.

5. A thumb sucking preventer comprising a plurality of longitudinally arranged wires adapted to inclose the thumb, certain of said wires terminating at the inner portion of the

thumb, other of said wires being relatively longer than said first-mentioned wires and adapted to extend over the back of the thumb, the inner ends of said last-named wires being bent to form eyes, means to secure the wires in spaced relation, and means engaging said eyes for fastening the device to the hand.

6. A thumb sucking preventer comprising 10 a plurality of longitudinally arranged wires, and a plurality of rings for holding said wires in spaced relation, said rings being disposed in a transverse plane with respect to said longitudinally extending wires.

7. A thumb sucking preventer comprising 15 a plurality of longitudinally arranged wires, and a plurality of rings for holding said wires in spaced relation, said rings being disposed in a transverse plane with respect to said longitudinally extending wires, said 20 rings being disposed parallel one with respect to the other.

In testimony whereof I affix my signature in presence of two witnesses.

ROY L. JACKSON.
